(57) **CLAIM**

The ornamental design for a mini radio, as shown and described.

DESCRIPTION

FIG. 1 is a top view of a mini radio showing my new design;

FIG. 2 is a bottom view thereof;

FIG. 3 is a front view thereof;

FIG. 4 is a right side elevational view thereof;

FIG. 5 is a left side elevational view thereof; and,

FIG. 6 is a rear view thereof.

The broken line showing of ear phones in FIG. 1 is for illustrative purposes only and forms no part of the claimed design.
